UNITED STATES PATENT OFFICE

LEWIS J. THOMAS AND AUBREY RIDDLE, OF EKRON, KENTUCKY

SMOKING PIPE

Application filed April 24, 1929. Serial No. 357,811.

This invention relates to smoking appliances and more particularly to a pipe by means of which tobacco is smoked.

When a tobacco pipe has been used for some time the smoke passage through its stem and mouth piece often becomes clogged by nicotine and, also, it often happens that saliva will pass through the smoke passage and cause the bowl in which tobacco is packed to become soggy. Therefore, one object of the invention is to provide a pipe which will not be liable to become clogged and which will not be liable to become soggy and strong by saliva working into the tobacco receiving chamber of the bowl.

Another object of the invention is to cause saliva which may work through the mouth piece of the pipe to be led through a separate passage in the stem of the pipe and delivered into a sub-chamber formed in the bowl beneath the tobacco receiving chamber where the saliva and nicotine will be subjected to heat so that the nicotine will be dried and the saliva converted into steam which passes from the sub-chamber through an opening or outlet.

Another object of the invention is to permit a false bottom which divides the bowl of the pipe into a tobacco receiving chamber and sub-chamber, to be removed, thereby permitting access to the sub-chamber so that it may be thoroughly cleaned when necessary.

Another object of the invention is to provide a pipe in which the mouth piece will be firmly but releasably held in engagement with the stem of the pipe by tubes constituting liners for the smoke passage and saliva passage.

The invention is illustrated in the accompanying drawings, wherein:

Figure 1 is a longitudinal sectional view through the improved pipe.

Figure 2 is a view showing the improved pipe principally in top plan and partially in section.

Figure 3 is a transverse sectional view taken on the line 3—3 of Figure 1.

This improved pipe includes a bowl 1 from which extends a stem 2 and a mouth piece 3

which may be formed of any material desired and is disposed in abutting end to end relation to the stem. A ferrule 4 of metal is provided about the outer end portion of the stem to reinforce it but the ferrule may be omitted if so desired. 55

In order to divide the bowl into a main tobacco receiving chamber 5 and sub-chamber 6, there has been provided a false bottom 7 consisting of a metal disc which fits snugly 60 within the bowl and rests upon an annular shoulder 8 formed in spaced relation to the lower end of the bowl. An opening 9 is formed centrally through the disc 7 and through this opening is passed a screw 10 65 which engages in the bottom of the bowl, as shown in Figure 1, and securely but releasably holds the false bottom in place. Therefore, the false bottom may be removed in order to permit access to the sub-chamber when 70 it is necessary to clean the same. In view of the fact that the false bottom is formed of metal it will become highly heated when the pipe is in use and this heat will cause saliva which accumulates in the sub-chamber to be 75 converted into steam. An outlet passage 11 for the steam leads from the sub-chamber and upwardly through the wall of the bowl. A liner 12 consisting of a metal tube is provided for the steam passage 11 and in order to reinforce the bowl about the upper end of the steam passage, there has been provided a guard consisting of a strip of sheet metal 13 which is secured by fasteners 14 driven into the wall of the bowl and formed with an 80 opening 15 registering with the steam passage.

A smoke passage 16 is formed longitudinally through the stem with its forward end communicating with the tobacco chamber 90 above the false bottom 7 and beneath this smoke passage is formed a saliva passage 17 leading from the sub-chamber for the full length of the stem and having communication with the smoke passage through a passage 18 95 formed vertically in the bowl in slightly spaced relation to the outer or rear end of the stem. By this arrangement, saliva may be led from the smoke passage into the saliva passage through which it will pass until it 100

reaches the saliva chamber. Nicotine will be carried through the saliva passage with the saliva and the heat radiating from the false bottom will cause the saliva to be changed into steam and the nicotine to be dried. A liner consisting of a tube 19 has been provided for the saliva passage and the smoke passage is lined by a similar tube 20, and from an inspection of Figures 1 and 3, it will be seen that these tubes are formed with side openings 21 and 22 disposed in opposed relation to each other and adapted to register with the passage 18. The tube 20 also constitutes a liner for the smoke passage 23 formed through the mouth piece 3 and fits tightly in the passage 23 so that when the mouth piece is drawn away from the stem in order to detach it, the tube 20 will be withdrawn from the smoke passage 16. By this arrangement the tube 20 may be thoroughly cleaned without danger of nicotine or saliva being forced from the tube into the bottom of the tobacco chamber. The tube 19 fits tightly in the saliva passage 17 and is of such length that its rear end projects from the stem and fits into a socket 24 formed in the mouth piece below the smoke passage 23. Therefore, the stem will be firmly held in engagement with the mouth piece and as air is sucked through the tube 20 when the pipe is in use, a very good draft will be provided. In order to prevent danger of the tube being bent there has been provided pins 25 which are threaded into the stem at opposite sides of the smoke passage and project from the stem for engagement in sockets 26 formed in the mouth piece. When this improved smoking pipe is in use, tobacco is packed into the bowl in the usual manner and smoke and air drawn from the bowl through the tube 20. Any nicotine or saliva which accumulates in the tube 20 passes through the passage 18 into the tube 19 and flows forwardly through this tube into the sub-chamber 6 where heat radiated from the false bottom will cause the saliva to be converted into steam and the nicotine to be dried. The steam passes out through the steam passage. It will thus be seen that saliva and nicotine will be prevented from accumulating in the bottom of the tobacco chamber and the pipe will be prevented from becoming soggy and strong. If the tube 20 becomes clogged the mouth piece is withdrawn from the stem and carries with it the entire smoke tube while the saliva tube will be left in the stem. A pipe cleaner can then be passed through the smoke tube in order to thoroughly clean it and the stem and mouth piece again assembled. If it is found necessary to also clean the saliva tube the false bottom can be removed after the screw 10 has been unscrewed and a pipe cleaner also passed through the saliva tube. The sub-chamber can be thoroughly cleaned in order to remove dried nicotine and the false

bottom then again set in place and secured by its securing screw. In view of the fact that the steam passage is lined by a metal tube and the bowl about the upper end of the steam passage is reinforced by a metal plate, there will be no danger of the upper end of the steam passage being clogged or broken through when a cake is formed in the bowl.

What is claimed is:

1. A smoking pipe comprising a bowl having a tobacco chamber and a sub-chamber beneath the tobacco chamber, a stem extending from said bowl and formed with a smoke passage leading from said tobacco chamber and a saliva passage leading from the sub-chamber and communicating with said smoke passage, a mouth piece abutting said stem and formed with a smoke passage registering with the smoke passage of the stem and a socket registering with the saliva passage, a tube extending through the smoke passage of the stem and mouth piece and removable with the mouth piece, and a tube extending through the saliva passage and projecting from the stem to fit into the socket of the mouth piece, said tubes having openings formed therein communicating with each other at the point of communication between the saliva passage and the smoke passage of the stem.

2. A smoking pipe comprising a bowl having a tobacco chamber and a sub-chamber, a stem extending from said bowl and formed with longitudinally extending passages, one being a passage opening into the tobacco chamber and the other a saliva passage opening into the sub-chamber, a connecting passage being formed transversely in the stem and opening into the smoke passage and saliva passage near the rear ends thereof, a mouth-piece abutting said stem and formed with a smoke passage registering with the smoke passage of the stem and a socket registering with the saliva passage, a tube extending through the smoke passage of the stem and mouth-piece, and a tube extending through the saliva passage and fitting into the socket of the mouth-piece, said tubes being formed with side openings communicating with each other through the connecting passage of the stem.

In testimony whereof we affix our signatures.

LEWIS J. THOMAS. [L.S.]

AUBREY RIDDLE. [L.S.]
